US0D1086084S

(12) **United States Design Patent** (10) **Patent No.:** **US D1,086,084 S**
Witzmann et al. (45) **Date of Patent:** **** Jul. 29, 2025**

(54) **DEFLATION BUTTON OF AN
IMPLANTABLE PENILE PROSTHESIS PUMP**

(71) Applicant: **Coloplast A/S**, Humlebaek (DK)

(72) Inventors: **Michael M. Witzmann**, Minneapolis, MN (US); **John J. Allen**, Mendota Heights, MN (US); **Megan Lenz**, Lino Lakes, MN (US)

(73) Assignee: **Coloplast A/S**, Humlebaek (DK)

(**) Term: **15 Years**

(21) Appl. No.: **29/920,373**

(22) Filed: **Dec. 11, 2023**

(51) **LOC (15) Cl.** **13-03**

(52) **U.S. Cl.** USPC **D13/174**

(57) **CLAIM**

The ornamental design for a deflation button of an implantable penile prosthesis pump, as shown and described.

DESCRIPTION

FIG. 1 is an isometric view of a deflation button of an implantable penile prosthesis pump.

FIG. 2 is a front side view thereof.

FIG. 3 is a back side view thereof.

FIG. 4 a top side view thereof.

FIG. 5 is a bottom side view thereof.

FIG. 6 is a left side view thereof; and,

FIG. 7 is a right side view thereof.

The broken lines in the drawings depict an implantable penile prosthesis pump that forms no part of the claimed design.

1 Claim, 7 Drawing Sheets
